UNITED STATES PATENT OFFICE.

ARTHUR ALLTREE, OF MANCHESTER, ENGLAND.

INTERNAL-COMBUSTION ENGINE.

1,010,566.

Specification of Letters Patent.

Patented Dec. 5, 1911.

Application filed January 19, 1910. Serial No. 538,885.

To all whom it may concern:

Be it known that I, ARTHUR ALLTREE, a subject of the King of England, residing at 279 Wilmslow road, Fallowfield, Manchester, in the county of Lancaster, England, have invented certain new and useful Improvements in Internal-Combustion Engines, of which the following is a specification.

My invention relates to internal combustion engines of the four-cycle type, the particular object of my invention being to provide improved means for controlling the admission and exhaust of the said engines.

According to my invention, I employ slide valves concentric with the working cylinder instead of the more usual puppet valve; and, in one arrangement of my invention, I employ segmental slide valves only, and in a second arrangement I employ the segmental slide valves in combination with a cylindrical slide valve.

In the former arrangement, in which the segmental slide valves only are employed, I arrange one such valve to control the exhaust port of the working cylinder and a second valve to control the admission port of the cylinder, each valve having a reciprocating sliding motion, and being so arranged that its slot or port is moved over the upper or lower parts (between which the cylinder ports are situated) of an expansion or like ring during its non-operative or closed period, each valve operating on its up-stroke for one cycle of operations and on its down-stroke for the next cycle, and so on.

In the second arrangement in which the segmental slide valves are arranged to act in combination with a cylindrical slide valve, I so arrange and operate the valves that their admission ports simultaneously register with the cylinder admission port for the intake stroke and their exhaust ports simultaneously register with the cylinder exhaust port for the exhaust stroke, the admission and exhaust ports in the cylindrical slide valve being moved over an expansion or like ring below the cylinder ports during the compression and firing strokes.

In the first arrangement, in which I employ segmental slide valves only, I prevent escape of the gases by using an expansion or segmental ring of special construction, but in the latter case, in which I also employ a cylindrical slide valve, I may use the special ring, or, alternatively, two separate rings.

Instead of forming the working cylinder and cylinder head in one piece I may make the head detachable and in any arrangement I may support the cylinder at its lower end. 60

The various valves may be driven from either one or two crank or eccentric shafts which are driven at the necessary speed by toothed gearing from the engine shaft.

I will now proceed to describe my invention in detail with reference to the drawings accompanying my specification.

Figure 1 is an end elevation, partly in section, of an engine according to one arrangement of my invention. 1 is the usual stationary working cylinder within which the piston 2 works. The cylinder 1 is formed with admission and exhaust ports 3, 4 respectively and an expansion or like ring 5, 6 is arranged around the combustion end of the cylinder, one part 5 of the ring being above the ports and the other part 6 below the ports. A segmental slide valve 7 formed with a slot or port 8 is arranged on the left side of the cylinder 1 and a similar segmental slide valve 9 formed with a slot or port 10 is arranged on the right side of the cylinder, the valve 7 controlling the admission port 3 and the valve 9 controlling the exhaust port 4. In practice the segments 7 and 9 may be made from a single cylindrical casting which may, after machining, be cut in two vertical halves or segments. Each segmental valve preferably fits closely around one half of the cylinder 1 but it is within the scope of my invention to vary the size of the segments if desirable. Each of the valves 7 and 9 is provided with a lug 11, 12, respectively, at, or near, its lower end, the lug 11 being connected by the rod 13 with the crank or eccentric shaft 14 and the lug 12 connected by the rod 15 with the crank or eccentric shaft 16, the crank or eccentric shafts being driven at quarter-time by suitable toothed gearing 17, 18, 19, from the engine shaft 20. The working cylinder 1 is provided with a water-cooled head 21 and a water-jacket 22, the latter having passages 23, 24 which coincide with the ports 3, 4 in the cylinder. 105 When the engine is working, the crank or eccentric shafts 14 and 16 give a reciprocating sliding motion to the segmental valves 7 and 9, and the arrangement is such that the slot 8 in the valve 7 coincides or 110 registers with the port 3 for the in-take stroke of the cycle, and the slot 10 in the

valve 9 registers with the port 4 for the exhaust stroke of the cycle. During the non-operative or closed period of each valve its slot is held over either the upper or lower part of the expansion or segmental ring 5, 6, which effectively closes or seals the slot, thus maintaining compression and preventing any escape of the gases. As shown in Fig. 1, the piston has just reached the end of the working stroke, and the slot 10 in the valve 9 is beginning to register with the port 4 for the exhaust stroke, and by the time the piston has completed half the stroke, the slot 10 and port 4 will be in full register. At the end of the exhaust stroke the slot 10 and port 4 will be out of register, the upward movement of the valve 9 having carried the slot 10 over the upper part 5 of the expansion ring, where it will remain during the next three strokes of the cycle. Just as the slot 10 moves out of register with the port 4, the slot 8 in the valve 7 begins to register with the admission port 3 for the intake stroke, and full register is reached when the piston has moved half way down on that stroke, and at the end of the stroke the slot 8 moves out of register with the admission port and over the lower part 6 of the expansion ring. The valves are so driven that each valve slot or port is moved over the upper part 5 of the expansion ring during its non-operative or closed period of one cycle of operations, and over the lower part 6 of the ring during its closed period of the next cycle of operations, and so on, the intake and exhaust taking place when the respective slots 8 and 10 are midway, or approximately midway, between the upper and lower parts of the expansion ring on both the upward and downward travel of the valves.

Fig. 2 is a sectional view showing how a detachable water-cooled head may be arranged in combination with the cylinder 1 and the water jacket. The detachable water-cooled head 21, fits within the end of the stationary working cylinder 1, and is suitably bolted to the casing 22. The detachable head is made compression tight by means of an expansion or like ring 25, and is formed with ports which coincide with the cylinder ports 3, 4. The lower end of the cylinder within which the piston works is preferably made thinner than the upper portion upon which the ring 5, 6 is fitted, as shown in the drawing. It will be understood that the object in making the head 21 detachable, is to permit access to the working cylinder 1, without having to remove the casing 22. Instead of, or in addition to, attaching the cylinder 1 to the cylinder head 21, I may bolt the lower end of the cylinder to the crank chamber casing, such an arrangement giving additional support to the cylinder, and preventing its oscillation when

subjected to the side thrust of the piston, with a consequent pinching of the valves.

A suitable flange, lugs, or the like 26 are cast on, or fixed to, the cylinder (as shown in Fig. 3) to receive the bolts by which it is secured to the crank chamber casing.

Fig. 4 is an external view of an upper part of the cylinder 1, and shows how the cylinder must be grooved to receive the special expansion or segmental ring. Two, preferably, parallel grooves 27, 28 are formed around the cylinder, and connected by two vertical grooves formed between the adjacent ends of the ports 3, 4, one groove 29 being shown in the drawing.

Figs. 5 and 6 show front and back views of the expansion ring 5, 6. The ring is preferably made in a single piece, cut vertically at one side to permit expansion, and shaped to fit in the parallel and vertical grooves described with reference to Fig. 4, and it will be seen that when in position on the cylinder the ring completely surrounds each port. The upper and lower parts 5, 6 of the ring are connected by cross-pieces 30, 31, which fit in the vertical grooves in the cylinder. Alternatively, however, I may form the ring in two vertical halves or segments by cutting it vertically through the cross-piece 31, similar to the cut shown in Fig. 5.

In the construction shown in Fig. 7, I employ two separate rings one above and one below the cylinder port. Fig. 7 is an end elevation, mainly in section, showing a modification of my invention, in which I arrange a cylindrical slide valve in combination with the two segmental slide valves above described. In this arrangement the cylindrical valve 32 fits slidably within the segmental valves 7 and 9, and concentrically around the cylinder 1, the admission and exhaust taking place at, and during, the correct period of the cycle by timing the movements of the cylindrical valve 32 and segmental valves 7 and 9, so that the slots 33 and 8 coincide with the cylinder port 3 for the intake stroke and the slots 34 and 10 coincide with the port for the exhaust stroke. As shown in Fig. 7, the piston 2 is nearing the end of the exhaust stroke and the cylindrical valve 32 has reached the end of its upward movement, the slots 32, 34, being partly closed by the upper ring 5. The segmental valve 9 is still traveling fast and upward and its slot 10 is nearly out of register with the slot 34, and just as the two slots move completely out of register the valve 32 is beginning to move slowly downward before the valve 9 reaches the end of its movement. As the segmental valve 7 has considerable lead on the cylindrical valve 32, it has attained a considerable speed when the valve 32 is commencing to move slowly downward and the slots 33, 34

and 8 begin to register just as the slots 34 and 10 move out of register, thereby putting the cylinder 1 in communication with the fuel supply for the intake stroke. The slots 33 and 1 are in full register by the time the piston has reached its maximum speed, and by this time the cylindrical valve 32 has begun to move rapidly, and at the end of the intake stroke both the slots 33 and 34 are moved over the ring 6 where they remain during the compression and firing strokes. Near the end of the firing stroke the slots 33, 34 begin to register with the cylinder port, the valve 32 having moved upward again, and simultaneously the slot 10 begins to register with the slot 34 for the exhaust stroke. It will be observed that the cylindrical valve 32 has considerable lead on the segmental valve 9, while the segmental valve 7 has considerable lead on the cylindrical valve 32, the latter being formed with a lug 35, and driven through the rod 36 from the half-time crank or eccentric shaft 16. In this arrangement, I show how the cylinder may be bolted to the crank chamber casing instead of being fixed to the cylinder head. A flange or lugs 26 formed on, or fixed to, the lower end of the cylinder is bolted, along with the casing 22 to the crank chamber casing 37. Instead of constructing the engine with a water-cooled head and jacket, I may employ a system of air-cooling in which heat radiating ribs or flanges are formed on the outer jacket and 35 ribs or fins on the head (which may be integral with the cylinder or detachable therefrom) such a construction being chiefly intended for motor-cycles and similar uses where this form of air-cooling is possible and desirable.

Fig. 8 is an end elevation, partly in section, of such an engine, the general arrangement of parts and the action appertaining thereto being on the lines of Fig. 1. The detachable head 21 is formed with ribs 38 which converge toward the center of the head, or approximately so, and extend downward to the dome of the combustion chamber. The working cylinder 1 is formed with a flange 39 and the outer casing 22 is formed with a flange 40, the detachable head being bolted to the two flanges, as shown in the drawing and the casing 22 bolted to the crank chamber casing 37. Ribs or flanges 41 are formed upon and encircle the casing 22 and suitable admission and exhaust passages 23, 24 are provided, as shown. The segmental slide valves 7 and 9 are driven from the same crank or eccentric shaft 14, the ends of the rods 13, 15 pivoting upon studs 42 and 43 respectively. The action is similar to that described with reference to Fig. 1.

The modification shown in Fig. 7 may be air-cooled in like manner.

In any arrangement of my invention I may make the various slots or ports in the form of a single slot or as two or more slots.

I may also cut lubricating oil channels on the various stationary and sliding members 70 and such channels are indicated by the number 44 throughout the drawings.

Access to the rods 13, 15 may be obtained through suitable inspection doors 45 formed in the casing 22, and a suitable air vent or 75 cock may be fitted in the head to ease compression, when desired.

My invention may be applied to engines having any number of cylinders, and arranged in any position, and although primarily intended as a high-speed engine for motor vehicles and the like may also be 80 constructed as a stationary engine.

Having now described my invention, what I claim as new, and desire to secure by Letters Patent is:—

1. In an internal combustion engine, a stationary working cylinder, having inlet and exhaust ports, a pair of segmental or half-cylindrical slide valves having ports 90 and disposed around said cylinder; and means for operating the said segmental slide valves to bring their ports respectively into register with the inlet and exhaust ports of the working cylinder on both the up-stroke 95 and down-stroke of the valves.

2. In an internal combustion engine, a stationary working cylinder, having inlet and exhaust ports, a pair of segmental or half cylindrical slide valves having ports 100 and disposed around said cylinder; means for operating the said segmental slide valves to bring their ports respectively into register with the inlet and exhaust ports of said cylinder on both the up-stroke and down-stroke of the valves, and a cooling jacket around the slide valves.

3. In an internal combustion engine, a stationary working cylinder, having inlet and exhaust ports, a pair of segmental or 110 half cylindrical slide valves having ports and disposed around said cylinder; means for operating the said segmental slide valves to bring their ports respectively into register with the inlet and exhaust ports of said cylinder on both the up-stroke and down-stroke of the valves, and a compression-retaining ring surrounding the inlet and exhaust ports of said cylinder both circumferentially and vertically.

4. In an internal combustion engine, in combination, a stationary cylinder, a cylindrical slide valve disposed around said inner cylinder, a pair of segmental or half-cylindrical slide valves disposed around said cylindrical slide valve; and means for operating the said valves, respectively.

5. In an internal combustion engine, in combination, a stationary cylinder, a piston therein, a cylindrical slide valve disposed 130

- around said inner cylinder, two segmental or half-cylindrical slide valves having ports and disposed around said cylindrical slide valve; a compression-retaining ring at the 5 inner end of said cylinder over which the valve ports may be moved during the compression and firing strokes of the piston; and means for operating the said valves respectively.
- 10 6. In an internal combustion engine, a stationary cylinder; having inlet and exhaust ports; two segmental or half-cylindrical slide valves having ports and disposed around the said cylinder; means for operating the said segmental slide valves to bring their ports respectively into register with the inlet and exhaust ports of said cylinder
- on both the up-stroke and down-stroke of the valves, and a detachable cooling head for said cylinder.
7. In an internal combustion engine, in combination with a stationary cylinder, a cylindrical slide valve disposed around the same; two segmental, or half-cylindrical slide valves disposed around said cylindrical slide valve; means for operating the said valves respectively, and a detachable cooling head for said cylinder.

In testimony whereof I affix my signature in presence of two witnesses.

ARTHUR ALLTREE.
